CLAIM

The ornamental design for a diaper caddy, as shown and described.

DESCRIPTION

FIG. 1 is an isometric view of a diaper caddy showing my new design.

FIG. 2 is a left side elevation view of the diaper caddy of FIG. 1.

FIG. 3 is a right side elevation view of the diaper caddy of FIG. 1.

FIG. 4 is a front elevation view of the diaper caddy of FIG. 1.

FIG. 5 is a rear elevation view of the diaper caddy of FIG. 1.

FIG. 6 is a top plan view of the diaper caddy of FIG. 1; and, FIG. 7 is a bottom plan view of the diaper caddy of FIG. 1. The dashed lines show features that do not form a part of the claimed design and the dot-dash lines show a boundary of the claimed design.

1 Claim, 7 Drawing Sheets
